UNITED STATES PATENT OFFICE.

HARRIS MITTLEBERG, OF NEW YORK, N. Y., ASSIGNOR TO AMERICAN INVISIBLE STITCHING MACHINE CO., INC., A CORPORATION OF NEW YORK.

SEWING-MACHINE ATTACHMENT.

1,300,184.

Specification of Letters Patent. Patented Apr. 8, 1919.

Application filed February 20, 1917. Serial No. 149,917.

To all whom it may concern:

Be it known, that I, HARRIS MITTLEBERG, a subject of the Czar of Russia, residing at New York city, in the county of New York and State of New York, have invented certain new and useful Improvements in Sewing-Machine Attachments; and I do hereby declare the following to be a full, clear, and exact description of the invention, such as 10 will enable others skilled in the art to which it appertains to make and use the same.

This invention relates to sewing machine attachments, and more particularly to that type of attachment for permitting a machine of ordinary construction to produce work ordinarily done on specially constructed sewing machines.

It has for an object, to provide an attachment which produces blind stitching on an ordinary sewing machine.

A further object of this invention is the provision of a presser foot for attachment to an ordinary machine, by which, the needle may pass through the under face of a superimposed ply of fabric without passing entirely through both faces of the fabric.

A further object is the provision of a presser foot having extensions or feet of different thicknesses, so that one foot bears on 30 a single ply of fabric, while the other bears upon a super-imposed folded ply.

A further object is the provision of a presser foot for a sewing machine having one foot thereof adjustably carried to accommodate the presser foot to all fabrics.

A further object of this invention is the provision of a presser foot having one foot of a greater thickness than the other to form a stop and guide for a folded ply of fabric, 40 and having a vertical recess formed in the guiding face, through which the needle partly passes.

Further objects will be apparent from the following specification, appended claims, and drawings, in which.

Figure 1 is a perspective view of a portion of a sewing machine showing this device applied thereto,

Figs. 2, 3 and 4 show different methods of 50 mounting the adjustable presser foot.

Fig. 5 is a cross sectional view showing the manner of guiding the needle through the fabric.

Heretofore, it has been necessary to provide a specially constructed sewing machine

to produce blind stitching for garments and the like, where linings are desired to be secured therein in such a manner as to avoid the showing of such stitching on the outer garment, and in such cases, the needle has 60 had a horizontal or arcuate movement, but in this invention, the fabric is folded to expose the under face, and the stitching is done through the folded portion, so that when completed, the fabric may be flattened 65 out leaving the stitching unnoticeable. The result is accomplished by using the ordinary vertically movable needle bar with a slightly altered presser foot.

Referring now to the drawings, and especially to Fig. 1 thereof, 10 indicates a part of the head of a sewing machine, having the needle bar 11 slidably mounted therein, to which bar the needle 12 is secured. The presser foot bar 13 is also slidable in the 75 head and this bar carries a presser foot 21, which is detachably mounted thereon. This presser foot is recessed or cutaway, as at 22, and is provided with the head 23 through which passes the bar 24, which is held in 80 position in said head as by the set screws 27, which extend through collars 26 which engage the head upon either side thereof, and are locked in position by the set screws 27. The bar 24 is bent to form the depending leg 85 28, which terminates in the foot 29, having the groove or notch 30 formed therein.

The foot 29 is provided with a depending ridge as clearly shown in Fig. 5 of the drawings, the lower edge of which terminates below the surface of the presser foot 21. This ridge forms a stop for the folded ply of fabric, and also presses the ply of the fabric 56 against the serrated feeding face of the sewing machine. The folded fabric is shown 95 at 57, and the nap of the fabric along the fold extends underneath the notch 30 of the foot 29, so that the needle will pass therethrough.

In Fig. 2 a head 31 is provided to fit upon 100 the presser foot bar, and this head has a set screw 32 by means of which it may be locked thereon. This head has a passageway 33, through which passes the bar 34, and said bar is locked in the head, as by 105 means of the set screw 35. A block 35' is carried by the bar 34, and this block has a passageway in which a stem from the socket member 36 is locked as by means of the set screw 37. In this socket member a bar 38 110

is adjustably mounted and held as by means of the set screw 39. The bar 38 is bent to form the foot 40, which has the guiding groove 41 formed therein.

5 In Fig. 3 the head is shown at 42, and in this head the bar 43 is held by the set screws 44, and the collar 45, which are locked on the bar by the said set screws. This bar depends, as at 46, to form the foot 47 in which 10 the needle guiding groove 48 is formed.

In the embodiment of my invention shown in Fig. 4, there is shown the bar 49 which supports the head 50, which is held thereon as by means of the screw 51, and this head

15 carries the bar 52, fastened thereto as by means of the set screw 53, said bar being bent to form the foot 54 provided as at 55 with the guiding groove.

Having thus described the construction 20 of my invention, the operation thereof may now be understood:

In Fig. 5 the needle is shown as about 25 ready to pass through the recess between the feet 21 and 29, and through the groove 30 formed in the foot 29. As already stated, the ridge upon the bottom of the foot 29 serves as a stop for the folded ply of a fabric, permitting the needle to pass through the superimposed ply of fabric without passing 30 entirely through the faces of the fabric. Thus the blind stitching is accomplished in an exceedingly simple and efficient manner.

Having thus described my invention what 35 I claim as new and desire to secure by Letters Patent is:

1. A sewing machine attachment of the class described comprising in combination a presser foot-bar, a presser foot detachably

carried by said presser foot-bar, a head having a transverse passage formed therein, a bar rotatably and longitudinally movable in said passage, locking means carried by said head for engaging this bar, a supplemental presser foot and guide carried by said bar having vertical and lateral adjustment with respect to said presser foot, and said supplemental presser foot having a vertical groove in the face thereof contiguous to said presser foot to receive portions of a folded section of fabric and the nap 50 thereon through which a vertically movable needle passes.

2. A sewing machine attachment of the class described, comprising a presser foot-bar, a presser foot detachably carried thereby, a head having a transverse passage formed therein, a bar rotatably and longitudinally movable in said passage, locking means carried by said head having engagement with said bar, a supplemental presser 60 foot adjustably carried by said bar, having vertical and lateral adjustment with respect to said presser foot, and said supplemental presser foot having a vertical passage formed in the face thereof contiguous to said presser foot through which a vertically reciprocating needle passes and in which, portions of a length of fabric in folded condition and nap of the fabric enter 65 to receive the vertical reciprocating needle. 70

In testimony whereof I affix my signature in presence of two witnesses.

HARRIS MITTLEBERG.

Witnesses:

JOSEPH NEMEROV,
DAVID FEICHE.
